UNITED STATES PATENT OFFICE.

FLORENCE B. HATCH, OF ST. LOUIS, MISSOURI.

DESIGN FOR A DOLL.

55,040.

Specification for Design.

Patented May 4, 1920.

Application filed November 24, 1919. Serial No. 340,419. Term of patent 7 years.

To all whom it may concern:

Be it known that I, FLORENCE B. HATCH, a citizen of the United States, residing at St. Louis, State of Missouri, have invented a new, original, and ornamental Design for Dolls, of which the following is a specification, reference being had to the accompanying drawing, forming a part thereof.

Fig. 2 is a side elevational view of a doll embodying my new design.

I claim:

The ornamental design for a doll, as shown.

FLORENCE B. HATCH.
